(57) **CLAIM**

The ornamental design for a ceiling fan housing, as shown and described.

DESCRIPTION

FIG. 1 is a perspective view of the ceiling fan housing showing my new design;

FIG. 2 is a front elevational view thereof, the right side elevational view, the left side elevational view and the rear elevational view being the same;

FIG. 3 is another elevational view thereof viewed from a direction midway between the front elevational view and the right side elevational view;

FIG. 4 is a top plan view thereof; and,

FIG. 5 is a bottom plan view thereof.

Any broken line illustration of environmental structure in the drawings is not part of the design sought to be patented.
